VEHICLE HEADLIGHT LAMP

Ernest Astor, Paris, France, assignor to General
Electric Company, a corporation of New YorkApplication April 21, 1932, Serial No. 606,633
In France May 4, 1931

4 Claims. (Cl. 176—34)

My invention relates to electric incandescent lamps and more particularly to headlight lamps for automobiles. Still more particularly my invention relates to means incorporated in the lamp 5 for eliminating glare.

One method of reducing glare and obtaining a low flat topped beam for use when approaching an oncoming vehicle is by providing a cup below a filament located ahead of the focal point of the 10 reflector. A second filament located at said focal point provides the driving beam. In practice, such lamps produce a certain amount of glare due to secondary light reflections which strike the leading-in wires and the stem press and are diffused thereby. The said secondary light reflections come from the bulb of the lamp or from the 15 lens of the headlight unit, particularly a fluted or striated lens. According to my invention this glare is eliminated by the use of screens or reflectors so disposed as to intercept the secondary light reflections before they strike the leading-in wires or the stem press.

Other features and advantages of my invention will appear from the following description of 25 species thereof and from the drawing.

In the drawing, Fig. 1 is a perspective view of a lamp comprising my invention; Fig. 2 is a plan view of a lamp located in a reflector; Fig. 3 is a diagrammatic side view of the lamp; Fig. 4 is a diagrammatic view of a lamp and reflector showing various reflected rays; and Figs. 5 and 6 are detailed perspective views of modifications of 30 one of the reflecting screens.

Referring to Fig. 1, the lamp comprises a base 10 and bulb 11 and filaments 12 and 13 in said bulb disposed on the axis thereof, filament 13 being located directly ahead of filament 12. Said filament 12, preferably V-shaped, is mounted on lead wires 14, 15 which are sealed in a stem press 16. 35 Filament 13, disposed along the axis of the bulb 11, is mounted at one end on a lead wire 17 which is sealed in the stem press 16 and at the opposite end on the edge of a cup-shaped reflector 18 mounted directly below said filament 13 on the lead wire 15. As shown in Fig. 2, the filament 12 is so located as to lie at the focal point 19 of a reflector 20. The cup 18 serves to limit the projection of light from the filament 13 to the upper 40 part of the reflector 20 from which it is directed below the horizontal as shown by a ray 21 in Fig. 4. A ray of light 22 also emanating from filament 13 may be reflected by the bulb at a so that it intersects the axis of the reflector and bulb at b. If there is no obstruction to the beam 45 at b, it will continue on to the reflector 20, striking

said reflector at c and being depressed below the horizontal toward d. However, if the ray should strike some obstacle at b, such as a stem press or lead wires, a portion of it would be diverted up to the reflector 20 at e, then outward above the horizontal toward f. Beams such as b, e, f would produce glaring spots in the upper 5 part of the reflector.

An observer whose eye is in the vertical plane passing through the axis of the reflector and 10 above the horizontal plane passing through said axis will see the bright spots, caused by images of the stem press and lead wires, on the vertical axis and above the horizontal axis. As the observer moves his eye laterally the images appear 15 to swing down toward the horizontal plane. According to my invention these images are eliminated by two screens 23 comprising metal strips adjacent to the stem press 16 and lead wires 15, 17 and extending beyond said stem press. Said 20 screens or shields 23 may be mounted on the lead wires 15, 17 along opposite sides of said stem press 16 and are preferably wide enough to extend above and below the stem press and lead wires.

On the other hand, an observer whose eye is in 25 the horizontal plane through the axis of the reflector will see no image of the stem press or lead wires if he is in the vertical plane through the axis. But if said observer is outside of the vertical axis he will see horizontal images of said 30 stem press and wires. These images are eliminated by preventing the rays from reaching said stem press by disposing a screen or shield 24 (Figs. 1 and 3) just beyond the edge of said stem press 16 and above the axis of the bulb and reflector. Said shield 24 may be mounted on the lead wires 15, 17, or it may be made integral with the shields 23 from a piece of suitably formed metal. As shown in Fig. 3, the shield 24 is preferably inclined forward and intercepts the 35 secondary rays which are reflected back from the bulb 11 and directs them back toward the reflector. The back of said shield 24 being unlighted will not give rise to brilliant spots in the 40 reflector. In Figs. 5 and 6 are shown modifications of the shield 24 comprising a rectangular sheet 25 in Fig. 5 and a sheet 26 in Fig. 6 curved 45 into an arc.

What I claim as new and desire to secure by 50 Letters Patent of the United States is:

1. In a lamp for vehicle headlamps, the combination of a bulb, a stem sealed therein having lead wires embedded in the press thereof, a filament supported by said stem and a pair of shields 55

- mounted adjacent to and on opposite sides of said stem press.
2. In a lamp for vehicle headlamps, the combination of a bulb, a stem sealed therein having lead wires embedded in the press thereof, a filament supported by said stem, a pair of shields mounted adjacent to and on opposite sides of said stem press, and a shield mounted just beyond the forward edge of said stem press and above the longitudinal axis of said lamp, said shield being inclined forward at an angle to said longitudinal axis of said lamp.
3. In a lamp for vehicle headlamps, the combination of a bulb, a stem sealed therein having lead wires embedded in the press thereof, a pair of filaments disposed substantially on the longitudinal axis of the lamp one ahead of the other, with a concave light reflector disposed under the forward filament, a pair of shields mounted adjacent to and on opposite sides of said stem
- 5
- press, and a shield mounted just beyond the forward edge of said stem press and above the longitudinal axis of said lamp, said shield being inclined forward at an angle to said longitudinal axis of said lamp.
4. In a lamp for vehicle headlamps, the combination of a substantially spherical bulb, a stem sealed to the rear wall of said bulb and having lead wires embedded in the press thereof, a filament in said bulb electrically connected to said lead wires and located between the center and the forward end of said bulb, said stem and filament being located substantially in the longitudinal axis of said lamp, a concave light reflector disposed below said filament and adapted 10 to reflect light therefrom upwardly, and a forwardly inclined shield mounted adjacent the forward edge of said stem press above the longitudinal axis of the lamp.
